UNITED STATES PATENT OFFICE.

FRANK B. JOHNSON, OF BOSTON, MASSACHUSETTS.

WINDOW-BLIND FASTENER.

1,203,351.

Specification of Letters Patent. Patented Oct. 31, 1916.

Application filed March 23, 1916. Serial No. 86,144.

To all whom it may concern:

Be it known that I, FRANK B. JOHNSON, a citizen of the United States, residing at Boston, in the county of Suffolk, State of Massachusetts, have invented certain new and useful Improvements in Window-Blind Fasteners; and I do hereby declare the following to be a full, clear, and exact description of the invention, such as will enable others skilled in the art to which it appertains to make and use the same.

This invention relates to window blind fasteners, and has for its primary object to provide a simple and efficient means capable of ready application to a window frame or casing, and which may be operated to retain a window blind in open position and to hold the same positively against being closed.

A further object of the invention is to provide a device of this character which is preferably so positioned upon a window frame or casing as to enable the same to be operated from within the room and without leaning out of the window or extending the hands or arms beyond the walls of the building to which the device is applied.

A further object of the invention is to provide a device of the character described which is of extremely simple and inexpensive construction, which may be attached to or detached from a window frame, which is positive in operation, and which will prove successful in the attainment of the ends for which it is designed.

With these objects in view, together with others which will appear as the description proceeds, the invention resides in the novel combination and arrangement of parts, all as will be described more fully hereinafter, illustrated in the drawings and particularly pointed out in the claims.

The invention will be best understood by reference to the accompanying drawings, wherein:

Figure 1, is a fragmentary side elevation of a portion of a window frame and illustrating the application of a fastener embodying my invention, Fig. 2, is a similar view illustrating the fastener swung to inoperative position. Fig. 3 is a top plan view of the fastener, partly in section, a portion of the fixed member being omitted, and Fig. 4, is a detail perspective view of the fastener removed from the frame.

Referring now more particularly to the

drawings, 5 indicates a fixed member, which in the present instance is in the form of a screw, having its shank twisted or coiled as at 6 adjacent its outer end, and having 60 its extremity bent to form a rest or support 7. This rest provides a channel, closed at its lower end, and open at its upper end as shown, the said channel being relatively narrow throughout its extent. 65 The screw member thus formed is adapted to be screwed or otherwise secured to the exterior of a window frame or casing with the said coil and support members protruding slightly beyond the lines of the 70 frame. It will be understood that there will be one of the above mentioned fixed or screw members at each side of the window frame, and preferably adjacent the inner edge of the said frame. 75

The blind holding means comprises an arm 8. This arm is provided as at 9 with a loop or coil member for engagement around the coil 6 upon the fixed or screw member, the said loop 9 being positioned 80 upon the stem or arm 8 inwardly a short distance from one extremity thereof, whereby a detent or projection 10 is formed at the arm extremity and lying in the same plane with the said arm. The above described arm at its opposite end is preferably enlarged as shown to provide a surface of sufficient area to engage against and retain a shutter against swinging movement. 85

The arm 8 may be formed of relatively heavy spring wire as shown, and the detent or projection 10 is so arranged as to engage when the arm is swung upon its loop 9 to vertical position, against the adjacent surface of the fixed member 5 to frictionally engage and retain the arm in vertical position. It is thus seen that the shutter retaining arm is securely held in inoperative position. When the arm 8 is swung downwardly with its loop 9 as a pivot the said arm enters and rests within the channel formed by the support 7, the said arm lying directly behind and engaging against the rear edge of an open shutter. Swinging 100 movement of the shutter upon its hinged portion will be prevented, and lateral movement of the arm 8 within the rest or support 7 will also be prevented. 105

When it is desired to close the shutter the 110 arm 8 may be raised from horizontal to vertical position, whereupon the shutter will

be free to be swung upon its hinges to closed position.

It is apparent that the simplicity of the device enables the same to be produced or manufactured at extremely low cost, and also enables the device to be readily and easily applied to or detached from a window frame or casing when desired.

While I have herein shown and described a particular or preferred embodiment of the invention, I wish it to be understood that I need not confine myself to all the precise details of construction herein set forth by way of illustration as modification and variation may be made without departing from the spirit of the invention or exceeding the scope of the claims.

What is claimed is:

1. In a device of the class described, a fixed member, a loop on said member, a rest adjacent said loop, an arm, a loop on said arm inclosing the loop on said fixed member and adapted to slide thereon, the said arm

being limited in its downward swinging movement by said rest, and the rear extremity of said arm being frictionally engaged with said fixed member, substantially as described.

2. In a device of the class described, a screw member, a loop on said member, a rest at the extremity of said member, an arm provided with a loop engaged within the loop of said screw member and adapted to swing thereon to vertical and horizontal positions, the said arm being adapted when swung to horizontal position to engage with said rest, and the rear end of said arm being adapted when swung to vertical position to frictionally engage with said screw member, substantially as described.

In testimony whereof, I affix my signature, in the presence of two witnesses.

FRANK B. JOHNSON.
